UNITED STATES PATENT OFFICE.

EDWARD R. IVES, OF BRIDGEPORT, CONNECTICUT.

DESIGN FOR A TOY CAR.

SPECIFICATION forming part of Design No. 25,722, dated June 30, 1896.

Application filed January 4, 1895. Serial No. 533,861. Term of patent 7 years.

To all whom it may concern:

Be it known that I, EDWARD R. IVES, a citizen of the United States, residing at Bridgeport, county of Fairfield, and State of Connecticut, have invented and produced a new and original Design for Toy Cars, of which the following is a specification, reference being had to the accompanying drawings, showing a part thereof.

10 This invention relates to a new and original design for a cast-metal toy car.

In the accompanying drawings, in which like letters of reference denote corresponding parts, Figure 1 is a perspective view of a car-body, showing my design. Fig. 2 is an end elevation of the same. Fig. 3 is a cross-sectional view of the same upon the line $x x$ of Fig. 1.

The leading features of my design consist 20 in the detail of a car-body cast in two parts. Said body is provided with, and has formed integral therewith, two series of openings in the sides, a door midway of said sides, lugs formed upon the ends of the body, and trucks 25 upon and under each side and end thereof.

Referring more particularly to the drawings, A represents a car-body which is cast in two

sections, which sections are substantially duplicates of each other. Said body has cast integral therewith and upon the bottom of the 30 ends thereof trucks B B, having openings a therein, and holes b to receive the spindle of the truck-wheel. (Not shown.) It is also provided at opposite ends with lugs C and D, which materially add to the appearance of 35 the design, the former serving to support the brake-rods and the latter affording means for connecting the cars together. Said car-body is further provided with openings F in the sides thereof, doorways G G midway of 40 said side, and flanges E beneath said doorway and extending the length of the side of the car-body.

What I claim is—

The design for a toy car substantially as 45 shown and described.

In testimony whereof I have signed my name to this specification in the presence of two subscribing witnesses.

EDWARD R. IVES.
